US0D1084136S

(12) **United States Design Patent** (10) Patent No.: **US D1,084,136 S**
(45) Date of Patent: ** Jul. 15, 2025

(54) **TRIGGER FOR ELECTRONIC
CONTROLLERS**

(71) Applicant: **SONY INTERACTIVE
ENTERTAINMENT INC.**, Tokyo (JP)

(72) Inventors: **Daisuke Kurihara**, Chiba (JP);
Masaho Morita, Tokyo (JP); **Takashi
Onda**, Saitama (JP)

(73) Assignee: **SONY INTERACTIVE
ENTERTAINMENT INC.**, Tokyo (JP)

(**) Term: **15 Years**

(21) Appl. No.: **29/883,032**

(22) Filed: **Jan. 23, 2023**

(30) **Foreign Application Priority Data**

Aug. 5, 2022 (JP) ..... 2022-016806 D

(51) LOC (15) Cl. 21-01

(52) U.S. Cl.

(57) **CLAIM**

The ornamental design for a trigger for electronic controllers as shown and described.

DESCRIPTION

FIG. 1 is a perspective view of front, top and left side of a trigger for electronic controllers showing our new design; FIG. 2 is a perspective view of rear, bottom and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a reference view of usage.

The broken lines shown in the drawings depict portions of the trigger for electronic controllers and form no part of the claimed design.

1 Claim, 7 Drawing Sheets
